FLUID PRESSURE SWITCH

Alex N. Szwargulski, St. Louis, and Paul R. Larson, Pine Lawn, Mo., assignors to Carter Carburetor Corporation, St. Louis, Mo., a corporation of Delaware

Application January 15, 1951, Serial No. 206,087

4 Claims. (Cl. 200—83)

1

This invention relates to fluid pressure actuated switches for electrical circuits.

The object of the invention is to provide a novel, simplified, inexpensive, rugged, and sensitive electrical switch which is actuated in response to a change in fluid pressure applied thereto.

This object and other more detailed objects hereafter appearing are attained by the device illustrated in the accompanying drawing in which:

Fig. 1 is a top view of the novel switch.

Fig. 2 is a vertical, transverse section through the switch.

Fig. 3 is a similar section, but showing the switch opened.

Fig. 4 is a top view of the adjustable plunger head disassembled.

Fig. 5 is a side view of the plunger head.

Fig. 6 shows a modified form of sealing grommet for the switch casing.

Fig. 7 is a detail section showing another modification.

The switch is mounted within a casing having a cylindrical side wall 8, a top wall 9, and a bottom wall 10 which includes a threaded fitting 11 for connection to a source of fluid pressure a change in which is to be sensed. The inner surface of wall 10 around fitting 11 is planar and a diaphragm 12 of suitable, flexible material, such as synthetic rubber, rests upon this surface and is secured thereto by the lower edge flange 13 of a cup-shaped member 14 received within the casing. The lower edge portion of casing wall 8 is annularly recessed, as at 15, to receive and clamp together wall 10, the diaphragm, and flange 13, to sealingly maintain the assembly. Casing wall 8 has an outward depression 16 which receives a lug 17 on the cup-shaped member to insure and maintain accurate assembly thereof.

Telescopingly received within cup member 14 is an opposing cup 20 which rests centrally upon diaphragm 12. A plunger shank 21 projects from the center of cup 20 and has a reduced, threaded portion 22 upon which is secured a head element 23 of plastic or other non-conducting material. This head element is non-circular, as shown in Fig. 4, and is slidably and non-rotatably received in a recess 24 formed in the base or top wall of member 14. A coiled spring 25 is compressed between member 14 and cup 20 and urges the cup into frictional engagement with the diaphragm and urges the diaphragm in opposition to the force of pressure applied through fitting 11.

An insulating gasket 26 is secured to the under-

surface of top wall 9 of the main casing and a spring strip 27 of general U contour has an extended base 27a secured by means of spaced rivets 28 which also secure a clip 29, with a terminal screw 30, to the top of the casing. Another insulating gasket 31 is interposed between the top of the casing and the clip. The free extremity of spring strip 27 carries a movable switch contact 32 in operative relationship with a stationary switch contact 33 mounted in the top of member 14. A kerf 34 is formed in the top of threaded plunger extension 22 for reception of a screw driver to adjust the plunger. The screw driver is introduced through an opening 35 in the casing top, normally sealed by an expansible cup element 36, and an aperture 37 in spring strip carrier 27. Certain features here shown are covered in a Patent No. 2,537,354 in the names of Korte and Szwargulski.

During normal operation, the frictional engagement between cup 20 and the diaphragm, induced by main switch spring 25, effectively resists unauthorized rotation of switch actuating plunger 21 and consequently, maintains the desired adjustment. On the other hand, adjustment may be effected, if desired, by the application of a screw driver to the plunger extension. Another important feature of the invention is the normal planar disposition of diaphragm 12 whereby its movements are restricted to one side of dead center namely, upward, and, accordingly, the diaphragm does not pass over center. It has been found that over center motion of the diaphragm results in erratic switch action.

The switch, which is normally closed, as in Fig. 2, may control a circuit for an indicator, such as an electric lamp. Under all normal running conditions of the engine, when the lubrication system is in proper order, the diaphragm will be urged upwardly, as in Fig. 3, opening the switch contacts. However, in case of failure in the lubricating system, these contacts will close, completing the indicator circuit so that the operator will be apprised of the failure before damage can result.

Figs. 6 and 7 show modified seals for the adjustment opening in the top of the casing. In Fig. 6, a rubber grommet 40 is inserted in opening 35 in place of the metal cup 36. In Fig. 7 clip 29 is eliminated and terminal screw 30a, itself, closes the adjustment opening. Rivets 28a secure together switch spring arm base 27a, gasket 26a, casing top wall 9a, gasket 31a of phenolic condensate or similar plastic material,

and a retainer plate 29a. Gasket 31a is originally provided with a central cylindrical hole somewhat smaller than the diameter of the terminal screw thread. The screw, then, cuts its own threads in the gasket to insure a moisture and dust proof fit.

The invention may be modified in various details as will occur to those skilled in the art and the exclusive use of all modifications as come within the scope of the appended claims is contemplated.

We claim:

1. In a fluid pressure switch, a fluid pressure connection having a surrounding wall, a flexible diaphragm clamped against said wall, a movable and a stationary switch contact on the opposite side of said diaphragm from said connection, a carrier for said movable contact, a member rigidly supported between said diaphragm and said movable switch contact and having a guide recess, said stationary contact being mounted on said member, a switch actuating plunger extending from said diaphragm to the proximity of said switch contact carrier, said plunger including shank and head parts threadedly connected for relative adjustment, one of said parts being slidably received in said guide recess to resist unauthorized rotation thereof, and a spring stressed between said member and said plunger for urging the latter and said diaphragm in opposition to the fluid pressure applied through said connection, said plunger also including a spring seat element rigid therewith and interposed between said spring and said diaphragm whereby said spring frictionally urges said plunger against said diaphragm to resist relative turning thereof.

2. A fluid pressure operated switch comprising a casing with one wall arranged for connection to a fluid pressure line, said wall having a planar inner surface, a flexible diaphragm normally resting on said surface, a cup-shaped member inside said casing and with its open edge resting on the periphery of said diaphragm and securing the same to said wall, said member having a central recess, stationary and movable switch points mounted within said casing, a shiftable element carrying said movable point and extending adjacent the base portion of said member, a plunger projecting through said base portion, said plunger including a foot element resting against said diaphragm, an actuator head slidably and non-rotatably received in said recess and adapted to move said shiftable element upon movement of said diaphragm, and a shank part rigid with said foot element and threadedly received by said head, and a spring urging said foot element against said diaphragm and said diaphragm to its rest position against said planar wall surface, said shank part of said plunger being presented for receiving a turning tool in adjusting said head and the frictional engagement between said foot element and said diaphragm resisting unauthorized turning of said shank part.

3. In a fluid pressure switch, a fluid pressure connection having a surrounding wall, a flexible diaphragm clamped against said wall, a movable

and a stationary switch contact on the opposite side of said diaphragm from said connection, a carrier for said movable contact, a member rigidly supported between said diaphragm and said movable switch contact and having a guide recess, said stationary contact being mounted on said member, a switch actuating plunger extending from said diaphragm to the proximity of said switch contact carrier, said plunger including shank and head parts threadedly connected for relative adjustment, one of said parts being slidably received in said guide recess to resist unauthorized rotation thereof, and a spring stressed between said member and said plunger for urging the latter and said diaphragm in opposition to the fluid pressure applied through said connection, said plunger also including a spring seat element rigid therewith and interposed between said spring and said diaphragm whereby said spring urges said plunger against said diaphragm, said plunger having a portion for accommodating a turning tool presented outwardly for adjusting said plunger, the frictional engagement between said diaphragm and said seat element resisting unauthorized turning of said plunger.

4. In a fluid pressure switch, a fluid pressure connection having a surrounding wall, a flexible diaphragm clamped against said wall, a movable and a stationary switch contact on the opposite side of said diaphragm from said connection, a carrier for said movable contact, a member rigidly supported between said diaphragm and said movable switch contact and having a guide recess, said stationary contact being mounted on said member, a switch actuating plunger extending from said diaphragm to the proximity of said switch contact carrier, said plunger including shank and head parts threadedly connected for relative adjustment, one of said parts being slidably received in said guide recess to resist unauthorized rotation thereof, and a spring stressed between said member and said plunger for urging the latter and said diaphragm in opposition to the fluid pressure applied through said connection, said plunger including a spring seat element rigid therewith and interposed between said spring and said diaphragm, said head part being slidably and non-rotatably received in said guide recess, said plunger being rotatable independently of said head element for adjusting the switch action and the frictional engagement between said diaphragm and said seat element resisting unauthorized turning of said plunger.
